J. C. FARRINGTON

FENCE GUARD

Filed March 26, 1924

UNITED STATES PATENT OFFICE.

JAMES C. FARRINGTON, OF LA FAYETTE, INDIANA.

FENCE GUARD.

Application filed March 26, 1924. Serial No. 701,934.

The object of my invention is to provide an attachment for fence posts, particularly metal fence posts having a T cross-section, by means of which guard wires may be supported at either side of the plane of the fence and at any desired height, depending upon the character of the stock against which the fence is to be protected.

The accompanying drawings illustrate my invention. Fig. 1 is a perspective view showing my improvement applied at two different heights upon a fence post. Fig. 2 is a fragmentary horizontal section showing means for supporting guard wire arm. Fig. 3 is a fragmentary perspective showing an improved clip for securing the barbed guard wires. Fig. 4 is a perspective of said clip. Fig. 5 is a perspective of a modified form, and Fig. 6 is a perspective view of a further slight modification.

In the drawings 10 indicates an L-shaped bracket, one leg of which is perforated at 11, 11 to receive the threaded legs 12, 12 of a post embracing clamp in the form of a U-shaped bolt 13 by means of which, and nuts 14, the bracket 10 may be secured to a fence post 15 so that one leg of the L-shaped bracket will lie in a plane at substantially right angles to the plane of the fence.

30 The last mentioned leg of bracket 10 is perforated at 16 to receive the clamping bolt 17 by means of which the wire supporting arm 18 may be attached to the bracket and held at any desired angle relative to the bracket. Arm 18 is formed to receive barbed guard wires 19, 19. For this purpose I prefer to perforate arm 18 at 20, 20 and attach the guard wires 19, 19 by means of a special clip 21 which is formed by doubling a length 40 of wire at its middle so as to form a bight 22 and bending the doubled portion, substantially medially at 23, so that the ends 24 will lie substantially at right angles to the portions of the wire forming bight 22, the distance between bight 22 and bends 23 being substantially equal to the distance between perforation 20 and the adjacent edge of arm 18, plus the diameter of wire 19, the construction being such that, wire 19 being laid

across and upon the edge of arm 18, clip 21 50 may be straddled upon wire 19 and ends 24 projected through perforation 20 and bent in opposite directions, as indicated in Fig. 3, to secure the parts in position.

It will be noted from Fig. 1 that if bracket 55 10 be secured to the post at or near its top, arm 18 may, without disconnecting wires 19, be swung from one side of the plane of the fence to the other, and may be held at any desired angle so as to protect the fence 60 from high-standing stock or against being climbed, and that the bracket 10 may be placed at an intermediate point in the height of the fence and arm 18 clamped in any desired position so as to protect the fence 65 against low standing stock.

It will be readily understood that my device may be readily attached to posts of forms other than that shown without departing from my invention. For instance, in 70 Fig. 5, I show a bracket 10' the post-leg of which is stiffened by a flange 10'' so that it may be attached to a round post by a post embracing clamp in the form of the bolt 26.

In Fig. 6 I show the bracket and guard 75 wire arm, illustrated in Fig. 1, applied by means of lag screws to a wood post.

I claim as my invention:

1. A fence guard comprising an L shaped bracket, means for securing one leg of the 80 bracket to the post with the legs of the bracket substantially at right angles to the post, and with the free leg of the bracket traversing the fence plane, and a wire carrying arm clamped to said free leg.

2. A fence guard comprising an L shaped bracket, a post embracing clamp associated with one leg of the bracket to secure the bracket to the post with the legs of the bracket substantially at right angles to the post 90 and the free leg of the bracket traversing the fence plane, and a wire carrying arm clamped to said free leg of the bracket.

In witness whereof, I have hereunto set my hand at La Fayette, Indiana, March, 95 A. D. one thousand nine hundred and twenty four.

JAMES C. FARRINGTON.
